RAILWAY TRACK CIRCUIT APPARATUS

Harold G. Witmer, Pittsburgh, Pa., assignor to
The Union Switch & Signal Company, Swiss-
vale, Pa., a corporation of Pennsylvania

Application November 9, 1934, Serial No. 752,291

14 Claims. (Cl. 246—34)

My invention relates to railway track circuit apparatus, and has for an object the provision of novel and improved apparatus for expediting the release of the track relay armature when a vehicle enters the section with which the track relay is associated. Apparatus embodying my invention also provides an improved shunting sensitivity for the track circuit. Other features and advantages of my invention will appear as the specification progresses.

I will describe two forms of apparatus embodying my invention, and will then point out the novel features thereof in claims.

The present application is a continuation of my copending application, filed August 23, 1933, Serial No. 686,425, for Railway track circuit apparatus, in so far as the subject matter common to the two cases is concerned.

In the accompanying drawing, Fig. 1 is a diagrammatic view showing one form of track circuit apparatus embodying my invention. Fig. 2 is a diagrammatic view showing a modified form of relay combination also embodying my invention.

25 In each of the views like reference characters designate similar parts.

Referring to Fig. 1, the reference characters 1 and 1a designate the traffic rails of a stretch of railway track which are formed by insulated rail joints 2 into a track section A—B. The track section A—B is provided with a track circuit which comprises as its essential elements the traffic rails bonded in the customary manner, a source of periodic current connected across the rails at one end of the section and a track relay adapted to receive energy from the traffic rails at the other end of the section. In Fig. 1, the secondary winding 3 of a track transformer T has one terminal connected with the rail 1a by a wire 4 and its opposite terminal connected with the rail 1 by a wire 5, a current-limiting resistor 6 being interposed in the wire 5. The primary winding 7 of the track transformer T is connected with any convenient source of periodic current such as an alternating current generator not shown in the drawing. It follows that the transformer T constitutes a source which continuously supplies alternating current to the traffic rails of the section A—B.

50 At the opposite end of the section A—B, a transformer T2 has its primary winding 8 connected with the rails 1 and 1a by wires 9 and 10, respectively, and hence the alternating current supplied to the traffic rails at the left-hand end 55 of the section induces a corresponding alternating

current in the secondary winding 11 of the transformer T2. Conductors 14 and 15 connect the secondary winding 11 of transformer T2 with the input terminals 12 and 13, respectively, of a voltage doubler network designated as a whole by 5 the reference character VD. The voltage doubler network VD includes two rectifying units R1 and R2 and two electrical condensers C1 and C2 connected to form a bridge circuit network, the arrangement being such that the rectifying units 10 R1 and R2 and the condensers C1 and C2 are each included in a respective arm of the bridge as will be readily understood by an inspection of the drawing.

A track relay TR is connected with the output 15 terminals 16 and 17 of the voltage doubler network VD by wires 18 and 19, respectively. The relay TR is preferably a direct current neutral relay of a type commonly employed with track circuit apparatus. The relay TR is provided 20 with an armature 20 which may be utilized for controlling traffic governing devices in any desired manner.

The voltage doubler circuit network VD functions in the following manner: During the half 25 cycle of the alternating current that the left-hand terminal of the secondary winding 11 is positive, current will flow over wire 14, input terminal 12, rectifying unit R1 in its low resistance direction, terminal 17 and into the condenser C1 and condenser C1 will take a sufficient charge to bring its plates to a difference of potential substantially equal to the maximum value of the electromotive force induced in the secondary winding 11, the plate towards the terminal 17 being the positive plate and the plate towards the terminal 13 being the negative plate. During this half cycle of the alternating current, current will also pass to the terminal 17 and thence through the winding of the relay TR by 30 35 40 45 50 55 a circuit to be shortly described.

On the next half cycle of the alternating current, the right-hand terminal of the secondary winding 11 will be positive and current will flow over wire 15, input terminal 13, condenser C2, 45 terminal 16, rectifying unit R2 in its low resistance direction, terminal 12 and wire 14 to the left-hand terminal of the secondary winding 11; and condenser C2 will take a sufficient charge to bring its plates to a difference of potential substantially 50 equal to the maximum value of the electromotive force induced in the secondary winding 11, the plate towards the terminal 13 being the positive plate and the plate towards the terminal 16 being 55

the negative plate. During this last mentioned half cycle of the alternating current, current will pass from the positive plate of the condenser C1, which condenser was charged during the previous 5 half cycle of the alternating current as described above, over terminal 17, wire 19, winding of the track relay TR, wire 18, terminal 16, rectifying unit R2, terminal 12, wire 14, secondary winding 11, wire 15, terminal 13 and to the negative plate 10 of the condenser C1, and relay TR will be energized. That is to say, the condenser C1 and the secondary winding 11 form two sources of electrical energy which function serially during this 15 half cycle to supply current to the winding of the relay TR. The electromotive force of the condenser C1 and that of the secondary winding 11 being additive in the circuit, the result will be that the electromotive force applied to the winding of the relay TR will be substantially double 20 that induced in the secondary winding 11. Furthermore, this circuit including the secondary winding 11, condenser C1, winding of the relay TR and rectifying unit R2 is a circuit comprising inductance, capacity and resistance, the parts of 25 which are preferably so proportioned and adjusted that the circuit is tuned to resonance at the frequency of the alternating current supplied by the track transformer T with the result that the current will have a maximum value. To 30 make the tuning effect more prominent, transformer T2 may be so designed as normally to operate on the non-linear portion of the saturation curve whereby a change in the current flowing in winding 8 will vary the inductance to de-tune the circuit which supplies current to relay 35 TR.

On the next half cycle of the alternating current, the left-hand terminal of the secondary winding 11 is again positive and current will flow 40 through the rectifier R1 to the terminal 17 and thence into the condenser C1, which was discharged during the previous half cycle of the alternating current, to again charge this condenser in the manner described hereinbefore. 45 During this half cycle of the alternating current, energy will pass from the positive plate of the condenser C2, which was charged during the previous half cycle, to the terminal 13 and thence over wire 15, secondary winding 11 of transformer 50 T2, wire 14, terminal 12, rectifying unit R1, terminal 17, wire 19, winding of relay TR, wire 18, terminal 16 and to the negative plate of the condenser C2, and relay TR will be energized. That 55 is to say, the condenser C2 and the secondary winding 11 now form two sources of electrical energy which function serially to supply current to the winding of the relay TR. The electromotive force of the condenser C2 and that of the secondary winding 11 being additive in the circuit, the result will be that the electromotive force applied across the winding of the relay TR will be substantially double that induced in the secondary winding 11. Furthermore, the circuit including the secondary winding 11, condenser C2, 60 winding of relay TR and the rectifying unit R1 is a circuit comprising inductance, capacity and resistance, the parts of which are preferably so proportioned that the circuit is tuned to resonance at the frequency of the alternating current supplied by the track transformer T with the result that the current will have a maximum 65 value.

It is clear from the foregoing description that during one half cycle of the alternating current induced in the secondary winding 11 of the trans-

former T2, the condenser C1 takes a sufficient charge to bring its plates to a potential difference substantially equal to the maximum value of the voltage induced in the secondary winding 11, and during the next half cycle of the alternating current, the condenser C1 discharges in series with the secondary winding 11 through the rectifying unit R2 to energize the winding of the track relay TR. Likewise, condenser C2 is charged during one half cycle of the alternating current induced 10 in the secondary winding 11 to bring its plates to a potential difference substantially equal to the maximum value of the voltage of the secondary winding 11 and then during the next half cycle of the alternating current, the condenser C2 discharges in series with the secondary winding 11 through the rectifying unit R1 to energize the winding of the track relay TR. The arrangement is such that the condensers C1 and C2 are charged during opposite half cycles of the alternating 15 current and hence discharge alternately. Consequently, an electromotive force of substantially double that induced in the secondary winding 11 is applied across the winding of the track relay TR during the full wave of the alternating current, the rectifying units R1 and R2 being so arranged that the current flows in the winding of the relay TR always in the same direction. The two receiving circuits over which the opposite half cycles of the alternating current are supplied to the relay TR being tuned to resonance at the frequency of the alternating current, the current will have a maximum value. It is to be noted that the current supplied to the relay TR is proportional to the capacity of the condensers 35 C1 and C2. The condensers C1 and C2 and the associated apparatus are so proportioned that the required working value of current necessary for relays of the type here involved is assured.

When a train enters the section A-B and 40 shunts the traffic rails, the voltage across the primary winding 8 of the transformer T2 will be greatly reduced and the voltage induced in the secondary winding 11 will be correspondingly reduced, and in turn, the unidirectional current supplied to the relay TR will be reduced to release the armature 20. Furthermore, the shunting of the primary winding 8 of the transformer T2 will be effective to vary the inductance of the secondary winding 11, and, consequently, the circuit 45 including the secondary winding 11, condenser C1 and winding of the relay TR; and the circuit including the secondary winding 11, condenser C2 and the winding of the relay TR will both be de-tuned, which will effect a still further reduction in the current flowing in the winding of the relay TR with the result that the release of the armature 20 will be expedited.

It should be noted that dependence need not be placed alone on the change in inductance occasioned by the shunting of the primary winding 8 by the train, for the improvement in shunting sensitivity, as considerable improvement can be obtained without resorting to the tuned circuit. As is well known, the copper oxide rectifier (as 65 well as certain other rectifiers of this type, such as the selenium rectifier) possesses the property of increasing its resistance to a marked extent with a relatively small decrease in potential across its terminals. Therefore, when a train enters 70 the section, and reduces the voltage of winding 11, the rectifier resistance is considerably increased and if the parts are properly proportioned, this increased resistance will prevent condensers C1 and C2 from reaching their peak charge corre- 75

sponding to the maximum voltage of winding 11, during the half-wave period when the charging current is effective. Consequently, the voltage across relay TR will be reduced in greater proportion than the voltage of winding 11, and increased shunting sensitivity will therefore result.

I have found that by using properly matched apparatus the shunting time for the track relay TR will be materially reduced from that obtained by customary contemporary track circuit apparatus. Furthermore, I have found that with track circuit apparatus embodying my invention, the shunting sensitivity of the track circuit is materially increased over that obtained in present day practice.

In Fig. 2, the input terminals 12 and 13 of the voltage doubler network VD are connected directly with the traffic rails 1 and 1a by wires 9 and 10, respectively, the transformer T2 of Fig. 1 being omitted. The winding of the track relay TR is connected with the output terminals 16 and 17 of the voltage doubler VD the same as in Fig. 1. During the half cycle of the alternating current that the traffic rail 1 is positive the condenser C1 takes a charge sufficient to bring the potential difference of its plates substantially to the maximum value of the voltage across the traffic rails, and then during the next half cycle, the condenser C1 discharges in series with the source of current for the track circuit through the winding of the relay TR with the result that the voltage applied across the relay TR is substantially double the voltage across the traffic rails. During the half cycle that the traffic rail 1a is positive, the condenser C2 takes a charge sufficient to bring the potential difference of its plates substantially to the maximum value of the voltage across the traffic rails, and then on the next half cycle of the alternating current, the condenser C2 discharges in series with the source of alternating current through the relay TR with the result that during this half cycle, a voltage substantially double that existing across the traffic rails is applied to the track relay TR. It is clear that the apparatus of Fig. 2 will be effective to quickly release the armature of the track relay TR in response to a train entering the associated section in the same manner as described for the apparatus of Fig. 1, dependence being placed on the voltage-resistance characteristic of the rectifier, or the change in inductance of the track circuit when shunted by a train, or on both of these factors.

Track circuit apparatus such as here disclosed will be effective to give a very quick release action of the track relay in response to a train entering the section, and the track relay will shunt with a relatively high resistance across the traffic rails.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination with a section of railway track and a source of periodic current connected across the traffic rails of the section, a direct current relay, a circuit network comprising four arms two successive arms of which each include an asymmetric unit and two successive arms of which each include a condenser, means for sup-

plying the periodic current from the traffic rails across the terminal common to the two arms including the asymmetric units and the terminal common to the two arms including the condensers, means for connecting the winding of said relay across the terminal common to an arm including one asymmetric unit and the arm including one condenser and the terminal common to the arm including the other asymmetric unit and the arm including the other condenser, and a traffic governing armature controlled by said relay.

2. In combination with a section of railway track and a source of periodic current connected across the traffic rails of the section, a direct current relay; a bridge circuit network comprising a first arm including a first asymmetric unit, a second arm including a first condenser, a third arm including a second condenser and a fourth arm including a second asymmetric unit; means for supplying the periodic current from the traffic rails across the terminal common to the first and fourth arms and the terminal common to the second and third arms, means for connecting the winding of said relay across the terminal common to the first and second arms and the terminal common to the third and fourth arms, and a traffic controlling armature governed by said relay.

3. In combination with a section of railway track and a source of periodic current connected across the traffic rails of the section, a direct current relay; a bridge circuit network comprising a first arm including a first asymmetric unit, a second arm including a first condenser, a third arm including a second condenser and a fourth arm including a second asymmetric unit; a transformer having its primary winding connected across the traffic rails, means for connecting the secondary winding across the terminal common to the first and fourth arms and the terminal common to the second and third arms, and means for connecting the winding of said relay across the terminal common to the first and second arms and the terminal common to the third and fourth arms.

4. In combination with a section of railway track and a source of alternating current connected across the traffic rails of the section, a transformer having its primary winding connected across the traffic rails of the section to receive the alternating current, a direct current relay, a condenser, a first and a second asymmetric unit, means for connecting said condenser and the first asymmetric unit in series across the secondary winding of said transformer; and means for connecting the condenser, winding of said relay and the second asymmetric unit in series across the secondary winding of the transformer; said asymmetric units being arranged to pass currents of opposite polarities whereby the condenser takes a charge during one half cycle of the alternating current and then functions in series with the secondary winding of the transformer to supply current to the winding of the relay during the other half cycle of the alternating current.

5. In combination with a section of railway track and a source of alternating current connected across the traffic rails of the section, a direct current relay, a transformer having its primary winding connected across the traffic rails of the section, a condenser, a first and a second asymmetric unit, means for connecting said condenser and the first asymmetric unit in series across the secondary winding of the transformer

to charge the condenser during one half cycle of the alternating current; and means for connecting the condenser, winding of the relay and the second asymmetric unit in series across the secondary winding of the transformer to supply current of double the voltage of said transformer to the winding of the relay during the other half cycle of the alternating current.

6. In combination with a section of railway track and a source of alternating current connected across the traffic rails of the section, a transformer having its primary winding connected across the traffic rails to receive the alternating current, a direct current relay; a first receiving circuit including the secondary winding of said transformer, a first condenser, the winding of said relay and a first asymmetric unit in series; said first circuit tuned to resonance at the frequency of the alternating current and arranged to pass one half cycle of the alternating current; and a second receiving circuit including the secondary winding of the transformer, a second condenser, the winding of said relay and a second asymmetric unit; said second circuit tuned to resonance at the frequency of the alternating current and arranged to pass the other half cycle of the alternating current, whereby shunting of the traffic rails is effective to de-tune said circuits for expediting the release of the relay.

7. In combination with a section of railway track and a source of alternating current connected across the traffic rails of the section, a direct current relay, a condenser, circuit means for connecting said condenser across the traffic rails including a first asymmetric unit for charging the condenser during one half cycle of the alternating current, and a receiving circuit for connecting the winding of said relay across the traffic rails including said condenser and a second asymmetric unit for energizing the relay during the other half cycle of the alternating current, said receiving circuit tuned to resonance at the frequency of the alternating current whereby shunting of the traffic rails is effective to de-tune said circuit for expediting the release of said relay.

8. In combination with a section of railway track and a source of alternating current connected across the traffic rails of the section, a transformer having its primary winding connected across the traffic rails to receive the alternating current, a direct current relay, a condenser, means for connecting said condenser across the secondary winding of the transformer including a first asymmetric unit for charging said condenser during one half cycle of the alternating current, and a receiving circuit for connecting the winding of the relay across the secondary winding of the transformer including said condenser and a second asymmetric unit for energizing said relay during the other half cycle of the alternating current, said receiving circuit tuned to resonance at the frequency of the alternating current whereby shunting of the traffic rails is effective to de-tune said circuit for expediting the release of said relay.

9. In combination with a section of railway track and a source of periodic current connected across the traffic rails of the section, a direct current relay; a bridge circuit network comprising a first arm including a first copper oxide rectifier, a second arm including a first condenser, a third arm including a second condenser and a fourth arm including a second copper oxide rectifier; means for supplying the periodic current from

the traffic rails across the terminal common to the first and fourth arms and the terminal common to the second and third arms, means for connecting the winding of said relay across the terminal common to the first and second arms and the terminal common to the third and fourth arms, and a traffic controlling armature governed by said relay.

10. In combination with a section of railway track and a source of periodic current connected across the traffic rails of the section, a direct current relay; a bridge circuit network comprising a first arm including a first copper oxide rectifier, a second arm including a first condenser, a third arm including a second condenser and a fourth arm including a second copper oxide rectifier; a transformer having its primary winding connected across the traffic rails, means for connecting the secondary winding across the terminal common to the first and fourth arms and the terminal common to the second and third arms, and means for connecting the winding of said relay across the terminal common to the first and second arms and the terminal common to the third and fourth arms.

11. In combination with a section of railway track and a source of alternating current connected across the traffic rails of the section, a transformer having its primary winding connected across the traffic rails of the section to receive the alternating current, a direct current relay, a condenser, a first and a second copper oxide rectifier, means for connecting said condenser and the first copper oxide rectifier in series across the secondary winding of said transformer; and means for connecting the condenser, winding of said relay and the second copper oxide rectifier in series across the secondary winding of the transformer; said copper oxide rectifiers being arranged to pass currents of opposite polarities whereby the condenser takes a charge during one-half cycle of the alternating current and then functions in series with the secondary winding of the transformer to supply current to the winding of the relay during the other half cycle of the alternating current.

12. In combination with a section of railway track and a source of alternating current connected across the traffic rails of the section, a direct current relay, a transformer having its primary winding connected across the traffic rails of the section, a condenser, a first and a second copper oxide rectifier, means for connecting said condenser and the first copper oxide rectifier in series across the secondary winding of the transformer to charge the condenser during one half cycle of the alternating current; and means for connecting the condenser, winding of the relay and the second copper oxide rectifier in series across the secondary winding of the transformer to supply current of increased voltage to the winding of the relay during the other half cycle of the alternating current.

13. In combination with a section of railway track and a source of periodic current connected across the traffic rails of the section, a direct current relay; a bridge circuit network comprising a first arm including a first rectifier characterized by increased resistance with a decrease in potential applied thereto, a second arm including a first condenser, a third arm including a second condenser and a fourth arm including a second rectifier characterized by increased resistance with a decrease in potential applied thereto; means for supplying the periodic current from the traffic rails

across the terminal common to the first and fourth arms and the terminal common to the second and third arms, means for connecting the winding of said relay across the terminal common to the first and second arms and the terminal common to the third and fourth arms, and a traffic controlling armature governed by said relay.

14. In combination with a section of railway track and a source of alternating current connected across the traffic rails of the section, a direct current relay, a transformer having its primary winding connected across the traffic rails of the section, a condenser, a first and a second recti-

fier each characterized by increased resistance with a decrease in potential applied thereto, means for connecting said condenser and the first rectifier in series across the secondary winding of the transformer to charge the condenser during one half cycle of the alternating current; and means for connecting the condenser, winding of the relay and the second rectifier in series across the secondary winding of the transformer to supply current of increased voltage to the winding of the relay during the other half cycle of the alternating current. 10

HAROLD G. WITMER.
